UNITED STATES PATENT OFFICE.

WALTER L. SIEWERS, OF WINSTON SALEM, NORTH CAROLINA.

SHIRT.

No. 879,685.

Specification of Letters Patent.

Patented Feb. 18, 1908.

Original application filed January 11, 1907, Serial No. 351,886. Divided and this application filed March 18, 1907. Serial No. 363,113.

To all whom it may concern:

Be it known that I, WALTER L. SIEWERS, a citizen of the United States, residing at Winston Salem, in the county of Forsyth 5 and State of North Carolina, have invented certain new and useful Improvements in Shirts; and I do hereby declare the following to be a full, clear, and exact description of the invention, such as will enable others skilled in the art to which it appertains to 10 make and use the same.

The invention comprises certain novel constructions, combinations and arrangements of parts as will be hereinafter fully described 15 and claimed.

In the accompanying drawings:—Figure 1 is a front elevation of a part of a shirt provided with a plurality of openings, and means for holding closed said openings. 20 Fig. 2 is a front elevation of a part of a shirt formed according to the present invention and having secured thereto a slightly modified form of fastening means. Fig. 3 is a detail, fragmentary rear view of a part of a 25 shirt provided with openings, with the securing means disclosed in Fig. 2 attached thereto.

In constructing a shirt or the like according to the present invention, I provide in the 30 fabric body portion a usual neck opening 1 which is designed to neatly fit around the neck of the wearer, and an opening in front for enlarging the neck opening in order to permit the head of the wearer to pass there- 35 through. The opening in front is formed by two slot-like openings as 2 and 3, leaving a tongue or intermediate portion 4 therebetween. The tongue 4 is formed by simply cutting the front of the shirt at 2 and 3 to any 40 desired distance, and then working the same with fancy work as 5, of any preferred kind. The tongue 4 is provided with apertures 6 and 7 and preferably neatly worked as an ordinary buttonhole. The apertures 6 and 45 7 may be positioned at any desired point near the upper end of tongue 4, but I prefer- ably place the same about midway from the center and the respective outer edges. The sides of the body fabric outside the openings 50 2 and 3 are provided with apertures 8 and 9 which are preferably worked similarly to apertures 6 and 7. In order to provide se- curing means for closing the openings 2 and 3 I use a ribbon, or tape or cord as 10, which 55 is designed to extend through aperture 8, apertures 6 and 7 and aperture 9 and may be

drawn tight for bringing the edges of the side portions of the body fabric toward the edges of the intermediate portion. Tape 10 may of course be tied as found desirable for holding the collar portion in position around the neck. This will firmly secure together the walls of the openings 2 and 3 and yet will obviate the necessity of using hooks and eyes, buttons and the like. 60

The ribbon or tape or cord 10 may be threaded through apertures 6, 7, 8 and 9 in any desired way, but I preferably pass the end of the tape 7 from the outside inward through aperture 8, then from the outside in- 70 wardly through aperture 6, thence outwardly through aperture 7 and again outwardly through aperture 9. This has somewhat the effect of weaving the tape 10 in and out so as to prevent the accidental removal of the 75 same, and also provide positive means for holding tongue 4 in a correct position.

In Fig. 2 will be seen a slightly modified form of securing means in which tongue 4 is not provided with apertures 6 and 7. A 80 ribbon as 10' is used and is passed through apertures 8 and 9 in any desired way, preferably as the same is passed through apertures 8 and 9 of the preferred structure. After the ribbon 10' has been placed in posi- 85 tion it is secured to tongue 4 in any desired manner, but preferably I sew the same centrally thereof near the upper end. In practical operation I find it advisable to simply sew the ribbon 10' in position on tongue 4 by 90 using a buttonhole worker with the knife re- moved so that there will be simply two rows of stitches as 11 and 12. It will, of course, be evident that the ribbon 10' may be sewed in position on tongue 4 before the same is in- 95 serted through apertures 8 and 9. When this is done each end of ribbon 10' will be passed through apertures 8 and 9 respec- tively and when it is desired to secure the openings 2 and 3 together the same is crossed 100 and tied, or if desirable tied in any conven- ient manner.

In order to form a firmer support or stronger base for the threads used in working apertures 6, 7, 8 and 9, and for threads 11 and 12, I provide any desired form of closely woven cloth as 13, 14 and 15. The pieces of reinforcing cloth 13, 14 and 15 are held in place by any usual fancy work that may be desired, as 16. As will be clearly seen from 110 Fig. 3 the reinforcing strip of cloth 14, forms a good base for threads 11 and 12 and will

firmly hold the ribbon 10' in position, and will not in the least strain or tear the shirt when the apertures 2 and 3 are drawn together by the ribbon.

5 I preferably use the reinforcing members 13, 14 and 15 in connection with both the preferred form shown in Fig. 1 and the modified form shown in Fig. 2, but as will be evident, I may dispense with the same. The 10 use of reinforcing strips, however, provides a stronger structure than are usually employed.

This is a divisional application of my co-pending application for shirts, filed Jan. 11, 15 1907, and bearing Serial No. 351,886.

Having thus fully described my invention, what I claim as new and desired to secure by Letters Patent is:—

1. In a shirt, a body portion of fabric having a neck opening and formed with slot-like 20 openings spaced apart and extending substantially longitudinally of the body portion

and opening into the neck opening, leaving an intermediate portion of the body fabric and side portions spaced therefrom, and a 25 tape connected to said intermediate portion and engaging said side portions for drawing the edges of the side portions toward the edges of the intermediate portion.

2. In a shirt, a body portion of fabric, a 30 neck opening, said body portion being formed with slot-like openings spaced apart and extending from the neck opening downwardly into the body portion leaving an intermediate portion of the body fabric and 35 side portions spaced therefrom, said side portions being formed with eyes and a tape engaging the intermediate portion.

In testimony whereof I affix my signature in presence of two witnesses.

WALTER L. SIEWERS.
